INVENTOR.

George Ferguson

UNITED STATES PATENT OFFICE.

GEORGE FERGUSON, OF WOLLASTON, MASSACHUSETTS, ASSIGNOR TO UNITED SHOE MACHINERY CORPORATION, OF PATERSON, NEW JERSEY, A CORPORATION OF NEW JERSEY.

RUBBER SOLE.

Application filed February 28, 1920. Serial No. 362,055.

To all whom it may concern:

Be it known that I, GEORGE FERGUSON, a citizen of the United States, residing at Wollaston, in the county of Norfolk and State of Massachusetts, have invented certain Improvements in Rubber Soles, of which the following description, in connection with the accompanying drawings, is a specification, like reference characters on the drawings indicating like parts in the several figures.

This invention relates to soles for shoes and is herein illustrated as embodied in a molded and vulcanized sole of rubber or rubber compound hereinafter referred to for convenience as rubber.

In the manufacture of rubber-soled turn shoes it is customary to use a rubber sole having a sewing rib or sewing shoulder and a feather. The rib or shoulder extends perpendicularly around the margin of the sole at a distance from the edge of the sole, the feather extending horizontally from the base of the rib or shoulder to the edge of the sole. In the manufacture of the shoe such a sole, together with an assembled upper and lining, are placed wrong side out upon a last and the upper and lining fastened to the sole by stitches which should extend through the base of the rib or shoulder. In the case of the usual sole no considerable difficulty is encountered in properly locating the stitches because the margin of the last used is curved downwardly and outwardly and the feather of the sole is similarly bent and held by the pulling-over and lasting operations so as to permit free access by the needle of the sewing machine to the base of the rib or shoulder. In the case, however, of a rubber sole which has a heel integral with it, a difficulty arises. The last used for such a sole is recessed at its heel end to receive the heel of the sole; and, both because of the shape of the recess and the thickness and consequent stiffness of the sole, it is impossible, or at least impracticable, to bend the feather downwardly about the heel end of the sole. When the feather is not bent downwardly the needle of the sewing machine is liable to enter the rib or shoulder at points located above the base with the result that there is looseness around the heel end of the shoe after it has been turned right side out and the seam is not as strong as it should be.

The general object of the present inven-

tion is to avoid these and similar undesirable results; and, to this end, the feather of the illustrative sole is inclined downwardly from the base of the sewing rib or shoulder to the edge of the sole around the heel portion of the sole. In the illustrative sole, the feather is beveled slightly in this locality to the end, as stated above, of permitting the needle of the sewing machine to pass through the base of the rib or shoulder.

Referring now to the accompanying drawings,—

Fig. 1 is a perspective of a sole in which the present invention is embodied;

Fig. 2 is a cross-section through the heel portion of the sole;

Fig. 3 is a cross-section through the forepart of the sole, and

Fig. 4 is a fragmentary cross-section through the forepart of a shoe having such a sole, showing the shoe on the last and the upper being fastened to the sole by stitches.

The illustrative sole comprises a sewing rib 5 the outer wall of which forms the usual sewing shoulder 7. The rib is spaced from the edge of the sole; and extending from the base of the rib to the edge of the sole is the feather 9. The sole also has a heel 10, which is integral with it and is provided with a gutter 11 and a raised middle filler portion 13. The sole is a molded and vulcanized one and has on its upper face and partly embedded therein a layer of fabric 15, such as canvas, the purpose of which is to strengthen the sole and particularly the rib.

In the process of incorporating such a sole in a shoe, the sole, together with an upper, which may or may not be lined, is placed wrong side out upon a last, the upper being then pulled-over and lasted and thereafter stitched to the rib. In Fig. 4 is shown a fragmentary cross-section through the forepart of the last and shoe, the upper being indicated at 17 and the needle of the sewing machine at 19. The needle passes through the rib 5 from outside to inside, the gutter 13 providing passageway for the needle after it emerges from the rib; and, in order to produce a strong, tight seam, it is desirable that the needle pass substantially through the base of the rib. In the forepart and shank of the sole there is no considerable difficulty in accomplishing this result, since the margin of the forepart and shank 110

of the last 21 is inclined downwardly and outwardly, as indicated at 23 and the margin of the corresponding part of the sole is bent down into contact with this surface 5 during the pulling-over and lasting operations and held in that position as shown in Fig. 4 with the obvious result that the needle of the sewing machine may readily pass through the base of the sewing rib 10 without digging into other parts of the sole. With a sole, however, which has a heel attached to it, a different condition obtains. The last in such case is, of course, recessed to receive the heel. The recess has a flat 15 bottom so that no bending down of the margin of the heel is possible; but even if the bottom of the recess were inclined downwardly, it would still be impossible, or at least impracticable, to bend the margin of 20 the heel downwardly and hold it bent because of the thickness and stiffness of the heel.

Accordingly, in the illustrated sole, the feather around the heel end of the sole is 25 molded so as to be inclined downwardly and outwardly (from the base of the rib to the edge of the sole) as shown best in Fig. 2. With this construction, there is no difficulty in securing a properly located seam 30 around the heel end of the sole as well as around the forepart and shank; and the beveling of the feather around the heel end of the sole is not objectionable both because it is comparatively slight and because the 35 combined thickness of the sole and heel at that locality is considerable.

Soles which contain several features of the illustrated sole not herein claimed, as well as molds for making the soles, are

shown, described and claimed in prior applications filed in my name Serial Nos. 188,174; 266,578; 318,728 and 352,024; and a mold for use in the manufacture of the illustrated sole is shown, described and claimed in application Serial No. 362,275 45 filed in the name of Knight and assigned to the same assignee as is the present application.

Although the invention has been set forth as embodied in a particular sole of vulcanized rubber, it should be understood that the invention is not limited in the scope of its application to the particular sole which has been shown and described.

Having thus described my invention, 55 what I claim as new and desire to secure by Letters Patent of the United States is:

1. A molded and vulcanized one-piece sole and heel adapted to be incorporated in a turned shoe, there being a sewing shoulder 60 and a feather extending around the sole, the feather around the heel portion of the sole being inclined downwardly away from the base of the sewing rib.

2. A molded and vulcanized one-piece sole 65 and heel adapted to be incorporated in a turned shoe, comprising a sewing rib projecting from the upper face of the sole, a feather located outside the rib and a gutter 70 located inside the rib, the feather around the forepart of the sole being substantially at right angles to the outer wall of the rib and around the heel portion being inclined downwardly away from the base of the rib.

In testimony whereof I have signed my 75 name to this specification.

GEORGE FERGUSON.
